[57] CLAIM

The ornamental design for a bud vase, substantially as shown.

DESCRIPTION

FIG. 1 is a front elevational view of a bud vase showing my new design, the rear being a mirror image thereof;
FIG. 2 is a side elevational view taken from the right of
FIG. 3, the side opposite being a mirror image thereof;
FIG. 3 is a fragmentary vertical sectional view taken in the direction of the arrows on line 3—3 of FIG. 1;
FIG. 4 is a top plan view thereof; and
FIG. 5 is a bottom plan view thereof.
